Inventor
Thomas Boudren

United States Patent Office.

THOMAS BOUDREN, OF BRIDGEPORT, CONNECTICUT.

Design No. 4,002, dated May 3, 1870.

DESIGN FOR GLASS COLUMN FOR COACH-LAMPS.

The Schedule referred to in these Letters Patent and making part of the same.

To all whom it may concern:

Be it known that I, THOMAS BOUDREN, of the city of Bridgeport, in the county of Fairfield, in the State of Connecticut, have originated and designed a new Pattern of Glass Column or Pillar for Coach-Lamps, of which the following is a full, clear, and exact description, reference being had to the accompanying drawings making a part of this specification.

Figure 1 is a front view of the pillar or column, which is made of glass, and cast or ground in such a manner as to be used in a coach-lamp, producing new and beautiful effects to the eye when so applied.

A is the base.

B is the cap.

C is the shaft, or part embraced between the cap and base A and B.

Figure 2 is a side view of the above.

Figure 3 is a sectional view of the shaft or part marked C.

Figure 4 is the same as fig. 1, ornamented by cutting in the front or back faces of the pillar or column.

Figure 5 is same as fig. 1, except being ornamented by the process known to the trade as glass-engraving.

What I claim is—

The design for a glass column or pillar for a coach-lamp, of the form and shape substantially as described and represented.

THOMAS BOUDREN.
